TUNING UNIT FOR CHOKE COILS

Myron J. Brown, Wilkinsburg, Pa., assignor to
Westinghouse Electric & Manufacturing Com-
pany, East Pittsburgh, Pa., a corporation of
Pennsylvania

Application December 31, 1939, Serial No. 310,473

20 Claims. (Cl. 171—242)

My invention relates to improvements in the tuning-unit assembly for a carrier-current resonant line choke-coil. These choke-coils consist of relatively large, hollow, air-core inductance-coils which are adapted to be connected in series with a transmission-line to carry the normal power-current, and to choke, or interpose impedance to, the flow of relatively weak, superimposed high-frequency currents through the choke-coil. These choke-coils have one or more so-called tuning-units disposed therein, and electrically connected across the terminals thereof, for the purpose of producing parallel-resonance to one or more carrier-current frequencies. These tuning-units invariably comprise a plurality of capacitors, with a terminal-board for changing the capacitor-connections to alter the tuning, and in my preferred form of embodiment, the tuning-units also embody a variometer which is utilized either as a vernier-means for tuning between the steps of the capacitor-connections, or, in some instances, as a shunt-connected inductance and auto-transformer for securing special effects such as are described in a copending application of E. T. Hughes and myself, Serial No. 315,384, filed January 24, 1940, for a Double-frequency resonant choke-coil. As these tuned or resonant choke-coils are designed, in general, for use in the open air, in series with a transmission-line conductor, it is highly desirable that the tuning-unit shall be enclosed in a water-tight casing. Due to the intense magnetic field within the interior of a resonant line choke-coil, the use of metal for enclosing the tuning-unit is frequently objectionable because of overheating-troubles due to eddy-currents.

The objects of my invention comprise the redesign of the above-described tuning-unit to incorporate constructional improvements such as the mounting of the electrical parts of the tuning-unit on a chassis or frame consisting of two rods which are supported from internal shoulders which are built into a porcelain cylindrical housing. A further structural improvement relates to the design and mounting of a removable water-tight end-cap or cover, the cover preferably having one or more terminals extending therethrough, said terminals terminating, at their inner ends, in flexible pigtails or wires which may be connected to the internal parts of the tuning-unit.

With the foregoing and other objects in view, my invention consists in the parts, apparatus, combinations, methods and systems hereinafter

described and claimed, and illustrated in the accompanying drawings, wherein:

Figure 1 is a longitudinal sectional view of a tuning-unit with the end-caps or covers removed, and with portions of the interior construction broken away as being immaterial to an understanding of the important features of my invention;

Fig. 2 is a reduced scale section on the line 10 II—II of Fig. 1;

Fig. 3 is a reduced-scale top plan-view of the cover or end-cap;

Fig. 4 is an elevational view of one end of the tuning-unit assembly, with the end-cap or cover 15 in place, and with parts broken away in section, to better illustrate the construction; and

Fig. 5 is a diagrammatic exploded view illustrating the electrical connections of the tuning-unit and the position of the tuning-unit within 20 a line-connected choke-coil.

As shown in Fig. 5, my tuning-unit is designed for mounting within a choke-coil 6 which is illustrated as being supported on a cylindrical, tubular, porcelain supporting-member 7, and as being electrically connected in series with a conductor 8 of a transmission-line. The tuning-unit consists essentially of a variable capacitance part, which is illustrated as comprising the four capacitors C₁, C₂, C₃ and C₄, the terminals of which 25 are connected, through insulated wires 9, to various binding posts 11 mounted on an insulating terminal-board 12 at one end of the tuning-unit. In my preferred form of construction, the tuning-unit also embraces a variometer L which has one or more terminals 13 which are brought through 30 one or more holes 14 in the terminal-board 12 for adjustable connection to different binding posts 11 or groups of binding posts 11.

As shown in Fig. 1, the electrical parts of my 40 tuning-unit, that is, the capacitors C₁ to C₄, the variometer L and the terminal-board 12 are mounted within a long, cylindrical, tubular casing 16 of insulating material, preferably porcelain. It is a distinctive feature of my invention that 45 the electrical parts of the tuning-unit are mounted on a rigid chassis or frame which comprises two long, longitudinally extending rods 17 on which all of these electrical parts are mounted, and said rods 17 are firmly supported, near one end of the tubular porcelain housing 16, by being bolted to an inner shoulder or boss 19 which is either formed integrally with, or firmly united to, the inside of the tubular porcelain housing 16. 50 As shown in Fig. 1, the mounting-connection between the rods 17 and the inner porcelain boss 19

is completed by means of two insulating plates 21 and 22 which are disposed on opposite sides of the boss or shoulder 19, and which are clamped between nuts 23 and 24 carried by the rods 17.

One end of the long chassis or frame, which is made essentially of the two long, longitudinally extending rods 17, is thus firmly secured to the essentially integral internal boss 19 of the tubular porcelain housing 16. As shown in Fig. 1, for convenience of illustration, this supported end of the chassis-rods 17 is illustrated as being the bottom end, although, in reality, the position of the tubular tuning-unit is almost invariably horizontal, as illustrated in Fig. 5. As shown in Fig. 1, the other end of the chassis-rods 17 of the tuning-unit terminate in the terminal-board 12 which also serves as a centering means for abutting against the inner surface or bore of the tubular porcelain housing 16. In the particular form illustrated, the edges of the terminal-board 12 are provided with adjustable abutment-screws 25 for making the centering contacts with the inner bore of the cylindrical housing 16. Between these two ends of the chassis-rods 17 are mounted the capacitors, such as the capacitors C₃ and C₄ (the remaining capacitors having been broken away in Fig. 1), and the variometer L, or rather the stator-member 26 of the variometer, the rotor-member 27 of the variometer being mounted on a shaft 28 which terminates in a tuning-knob 29 on the top of the terminal-board 12.

It will be noted that the internal construction of the chassis 17 is such as to avoid the use of metal having a considerable extent in a transverse direction, so as to avoid the development of excessive eddy-currents resulting from the alternating magnetic field which includes magnetic lines of force extending in the longitudinal direction, and thus tending to produce eddy-currents in transverse planes.

In the manner shown in Fig. 4, each end of the tubular casing 16 is tightly closed by a removable cover or end-cap 31 having one or more insulatedly bushed terminals 32 extending therethrough. In the illustrated embodiment of my invention, the cover or end-cap 31 is made of insulating material, specifically porcelain, having a centrally disposed terminal-rod 32 passing therethrough. At its outer end, the terminal-rod 32 terminates in a metal head or binding post 33 which is separated from the outer end of the insulating cap 31, by means of a washer 34. The inner end of the terminal-rod 32 is firmly clamped to the inner surface of the insulating cover 31, with the aid of washers 36 and a nut 37. A water-tight joint is made between the insulating cap 31 and the end of the tubular housing 16, by means of a washer 38 which is preferably cemented, at 39, to the cap-member 31. The inner end of the terminal-rod 32 also carries a flexible insulated conductor or pigtail 41 which is utilized to make detachable and adjustable connection to any one or more of the binding posts 11 of the terminal-board 12 of the tuning-unit.

The end-cap or cover 31 must be securely clamped or pressed against the end of the tubular porcelain housing 16, so as to compress the water-tight washer 38 sufficiently to make a water-tight joint, and this clamping connection should preferably be effected in a manner such that the end-cap 31 shall be readily removable and so that excessive eddy-currents shall not be generated as a result of the intense longitudinally extending magnetic field resulting from the 73

main line-connected choke-coil 6 (Fig. 5) which surrounds the tuning-unit.

As shown in Fig. 4, this clamping connection comprises an encircling metal clamping-ring 43 having split, flanged ends 44 and 45 which are connected by bolts 46, the bolts being insulated at at least one end, as indicated at 47, so as to break the flow of eddy-currents which would tend to flow circularly around the clamping-ring 43. The clamping-ring is engaged within a notch or shoulder-abutment 49 which is provided, for the purpose, around the outer surface of the tubular porcelain housing 16. Connected to the clamping ring 43 are a plurality of bolts 51 which engage a metallic clamping-casting 52 which fits over the end of the end-cap or cover 31, so as to clamp the end-cover 31 firmly in place, on the end of the tubular insulating housing 16. As shown in Fig. 3, one end of the clamping-casting 52 is split, as indicated at 53, in order to prevent eddy-current flow.

From the foregoing explanation, it will be seen that I have provided a simple, strong, internal chassis-construction, and external water-proof design, for my improved tuning-unit.

Electrically, as illustrated in Fig. 5, the unit is connected between the terminals of the line-connected choke-coil 6, by means of connectors 55 and 56. The connector 55 is connected to the terminal-cap 33 of the end-cover 31 at the end of the tuning-unit which has the flexible pigtail 41 which is connected to the selected terminals 11 of the terminal-board 12 of the capacitors C₁ to C₄. The other line-connector 56 is similarly connected to the other end-cap 31' at the other end of the tuning-unit, as shown in Fig. 5, this end-cap 31' having an internal pigtail 41' which is connected to one of the rods 17 of the tuning-element chassis, one terminal of the variometer 11 being grounded or connected on this same rod 17, as indicated at 57. The illustrated electrical connection is indicated only by way of illustration, as I am not limited to this particular form of connection or use of the tuning-element.

While I have illustrated my invention in a single form of embodiment which is at present preferred by me, I wish it to be understood that I am not altogether limited to this particular form of embodiment, as various changes may be made by those skilled in the art without departing from the essential features of my invention, particularly in its broader aspects. I desire, therefore, that the appended claims shall be accorded the broadest construction consistent with their language and the prior art.

I claim as my invention:

1. The combination, with a relatively heavy-duty, alternating-current, large-diameter line-connected choke-coil, of a relatively light-current tuning-unit disposed within said line-connected choke-coil, said tuning-unit comprising an open-ended tubular insulating casing, a readily removable water-tight cover for an open end of said tubular insulating casing, a variable capacitive impedance-device and means for adjusting the same disposed within said casing, with the adjustment-means accessible at the aforesaid open end, a chassis for supporting said impedance-device and said adjustment-means, said chassis comprising two longitudinally extending rods, and internal shoulder-means carried by said tubular insulating casing for supportingly engaging said rods independently of said cover.

2. The combination, with a relatively heavy-

duty, alternating-current, large-diameter line-connected choke-coil, of a relatively light-current tuning-unit disposed within said line-connected choke-coil, said tuning-unit comprising an open-ended tubular insulating casing having both ends open, a variable capacitive impedance-device and means for adjusting the same disposed within said casing, a separate, readily removable water-tight cover of insulating material for each open end of said casing, each cover comprising an insulatingly bushed terminal extending therethrough, a flexible connector for connecting the inner end of said terminal to said impedance-device, and fastening-means for each cover, each fastening-means comprising a split metallic band encircling said casing, the casing having a shoulder-abutment for retaining said band, said band including means for tightening it around the casing and for insulatingly blocking the flow of induced currents around the casing, and disengageable fastening-means for tightly drawing the associated end-cover to said band.

3. The combination, with a relatively heavy-duty, alternating-current, large-diameter line-connected choke-coil, of a relatively light-current tuning-unit disposed within said line-connected choke-coil, said tuning-unit comprising an open-ended tubular insulating casing, a variable capacitive impedance-device and means for adjusting the same disposed within said casing, a readily removable water-tight cover of insulating material for an open end of said casing, the adjustment-means being accessible at the aforesaid open end, and fastening-means for said cover, said fastening-means comprising a split metallic band encircling said casing, the casing having a shoulder-abutment for retaining said band, said band including means for tightening it around the casing and for insulatingly blocking the flow of induced currents around the casing, a metal clamping-member fitting over said cover, said metal clamping-member being split, and disengageable fastening-means for tightly drawing said clamping-member to said band.

4. The combination, with a relatively heavy-duty, alternating-current, large-diameter line-connected choke-coil, of a relatively light-current tuning-unit disposed within said line-connected choke-coil, said tuning-unit comprising an open-ended tubular insulating casing; a readily removable water-tight cover for an open end of said tubular insulating casing; a variable capacitive impedance-device, a variable inductive impedance-device and means for adjusting the same disposed within said casing, with the adjustment-means accessible at the aforesaid open end; a chassis for supporting said impedance-devices and the internal parts of said adjustment-means, said chassis comprising two longitudinally extending rods; and internal shoulder-means carried by said tubular insulating casing for supportingly engaging said rods independently of said cover.

5. A tuning-unit comprising an open-ended tubular insulating casing, a readily removable water-tight cover for an open end of said tubular insulating casing, a variable capacitive impedance-device and means for adjusting the same disposed within said casing, with the adjustment-means accessible at the aforesaid open end, a chassis for supporting said impedance-device and said adjustment-means, said chassis comprising two longitudinally extending rods, and internal shoulder-means carried by said tubular insulating casing for supportingly engaging said rods.

6. A tuning-unit comprising an open-ended tubular insulating casing having both ends open, a variable capacitive impedance-device and means for adjusting the same disposed within said casing, 5 a separate, readily removable water-tight cover of insulating material for each open end of said casing, each cover comprising an insulatingly bushed terminal extending therethrough, a flexible connector for connecting the inner end of said terminal to said impedance-device, and fastening-means for each cover, each fastening-means comprising a split metallic band encircling said casing, the casing having a shoulder-abutment for retaining said band, said band including means for tightening it around the casing and for insulatingly blocking the flow of induced currents around the casing, and disengageable fastening-means for tightly drawing the associated end-cover to said band.

7. A tuning-unit comprising an open-ended tubular insulating casing, a variable capacitive impedance-device and means for adjusting the same disposed within said casing, a readily removable water-tight cover of insulating material 20 for an open end of said casing, the adjustment-means being accessible at the aforesaid open end, and fastening-means for said cover, said fastening-means comprising a split metallic band encircling said casing, the casing having a shoulder-abutment for retaining said band, said band including means for tightening it around the casing and for insulatingly blocking the flow of induced currents around the casing, a metal clamping-member fitting over said cover, said metal clamping-member being split, and disengageable fastening-means for tightly drawing said clamping-member to said band.

8. A tuning-unit comprising an open-ended tubular insulating casing; a readily removable water-tight cover for an open end of said tubular insulating casing; a variable capacitive impedance-device, a variable inductive impedance-device and means for adjusting the same disposed within said casing, with the adjustment-means 40 accessible at the aforesaid open end; a chassis for supporting said impedance-devices and said adjustment-means, said chassis comprising two longitudinally extending rods; and internal shoulder-means carried by said tubular insulating casing for supportingly engaging said rods independently of said cover.

9. An open-ended tubular insulating casing, a readily removable water-tight cover for an open end of said tubular insulating casing, an adjustment-means accessible at the aforesaid open end, 55 a chassis comprising two longitudinally extending rods, and internal shoulder-means carried by said tubular insulating casing for supportingly engaging said rods.

10. An open-ended tubular insulating casing having both ends open, a separate, readily removable water-tight cover of insulating material for each open end of said casing, each cover comprising an insulatingly bushed terminal extending therethrough, and fastening-means for each cover, each fastening-means comprising a split metallic band encircling said casing, the casing having a shoulder-abutment for retaining said band, said band including means for tightening it around the casing and for insulatingly blocking the flow of induced currents around the casing, and disengageable fastening-means for tightly drawing the associated end-cover to said band.

11. An open-ended tubular insulating casing, 70 75 a readily removable water-tight cover of insu-

lating material for an open end of said casing, an adjustment-means accessible at the aforesaid open end, and fastening-means for said cover, said fastening-means comprising a split metallic band encircling said casing, the casing having a shoulder-abutment for retaining said band, said band including means for tightening it around the casing and for insulatingly blocking the flow of induced currents around the casing, a metal clamping-member fitting over said cover, said metal clamping-member being split, and disengageable fastening-means for tightly drawing said clamping-member to said band.

12. An open-ended tubular insulating casing, a readily removable water-tight cover for an open end of said tubular insulating casing, a chassis comprising two longitudinally extending rods, and internal shoulder-means carried by said tubular insulating casing for supportingly engaging said rods independently of said cover.

13. An open-ended tubular insulating casing, a readily removable water-tight cover of insulating material for an open end of said casing, and fastening-means for said cover, said fastening-means comprising a split metallic band encircling said casing, the casing having a shoulder-abutment for retaining said band, said band including means for tightening it around the casing and for insulatingly blocking the flow of induced currents around the casing, a metal clamping-member fitting over said cover, said metal clamping-member being split, and disengageable fastening-means for tightly drawing said clamping-member to said band.

14. The combination, with a relatively heavy-duty, alternating-current, large-diameter, air-core, outdoor choke-coil, of a relatively light-current adjustable unit disposed within said choke-coil, said adjustable unit comprising an open-ended tubular insulating casing, a readily removable water-tight cover of insulating material for an open end of said tubular insulating casing, a variable device and means for adjusting the same disposed within said casing, with the adjustment-means accessible at the aforesaid open end, a chassis for supporting said variable device and said adjustment-means, said chassis comprising two longitudinally extending rods, and internal shoulder-means carried by said tubular insulating casing for supportingly engaging said rods independently of said cover.

15. The combination, with a relatively heavy-duty, alternating-current, large-diameter, air-core, outdoor choke-coil, of a relatively light-current adjusting unit disposed within said choke-coil, said adjusting unit comprising an open-ended tubular insulating casing having both ends open, a variable electrical device and means for adjusting the same disposed within said casing, a separate, readily removable water-tight cover of insulating material for each open end of said casing, each cover comprising an insulatingly bushed terminal extending therethrough, a flexible connector for connecting the inner end of said terminal to said electrical device, and fastening-means for each cover, each fastening-means comprising a split metallic band encircling said casing, the casing having a shoulder-abutment for retaining said band, said band including means for tightening it around the casing and for insulatingly blocking the flow of induced currents around the casing, and disengageable fastening-means for tightly drawing the associated end-cover to said band.

16. The combination, with a relatively heavy-duty, alternating-current, large-diameter, air-core, outdoor choke-coil, of a relatively light-current adjustable unit disposed within said choke-coil, said adjustable unit comprising an open-ended tubular insulating casing, a variable electrical device and means for adjusting the same disposed within said casing, a readily removable water-tight cover of insulating material for an open end of said casing, the adjustment-means being accessible at the aforesaid open end, and fastening-means for said cover, said fastening-means comprising a split metallic band encircling said casing, the casing having a shoulder-abutment for retaining said band, said band including means for tightening it around the casing and for insulatingly blocking the flow of induced currents around the casing, a metal clamping-member fitting over said cover, said metal clamping-member being split, and disengageable fastening-means for tightly drawing said clamping-member to said band.

17. The combination, with a relatively heavy-duty, alternating-current, large-diameter, air-core, outdoor choke-coil, of a relatively light-current adjustable unit disposed within said choke-coil, said adjustable unit comprising an open-ended tubular insulating casing; a readily removable water-tight cover of insulating material for an open end of said tubular insulating casing; a plurality of variable electrical devices and means for adjusting the same disposed within said casing, with the adjustment-means accessible at the aforesaid open end; a chassis for supporting said electrical devices and the internal parts of said adjustment-means, said chassis comprising two longitudinally extending rods; and internal shoulder-means carried by said tubular insulating casing for supportingly engaging said rods independently of said cover.

18. An open-ended tubular insulating casing, a readily removable water-tight cover for an open end of said tubular insulating casing, an adjustment-means accessible at the aforesaid open end, a chassis comprising two longitudinally extending rods, internal shoulder-means carried by said tubular insulating casing for supportingly engaging said rods, and an adjustable device mounted on said chassis within the casing and operatively connected to said externally accessible adjustment-means.

19. An open-ended tubular insulating casing, a readily removable water-tight cover of insulating material for an open end of said casing, an adjustable device within the casing, an adjustment-means therefor accessible at the aforesaid open end, and fastening-means for said cover, said fastening-means comprising a split metallic band encircling said casing, the casing having a shoulder-abutment for retaining said band, said band including means for tightening it around the casing and for insulatingly blocking the flow of induced currents around the casing, a metal clamping-member fitting over said cover, said metal clamping-member being split, and disengageable fastening-means for tightly drawing said clamping-member to said band.

20. An open-ended tubular insulating casing, a chassis comprising two longitudinally extending rods, and internal shoulder-means carried by said tubular insulating casing for supportingly engaging said rods.

MYRON J. BROWN.
